OTHER PUBLICATIONS

Design U.S. Appl. No. 29/461,770 filed Jul. 26, 2013 titled Square-Shaped Suction Cup.

Primary Examiner — Sheryl Lane*Assistant Examiner* — Nicole Shiflet(74) *Attorney, Agent, or Firm* — Faegre Baker Daniels LLP(57) **CLAIM**

The ornamental design for a square-shaped suction cup, as shown and described.

DESCRIPTION

FIG. 1 is a front elevation view of a square-shaped suction cup according to the present application;

FIG. 2 is a rear elevation view of the square-shaped suction cup according to the present application;

FIG. 3 is a left side elevation view of the square-shaped suction cup according to the present application;

FIG. 4 is a right side elevation view of the square-shaped suction cup according to the present application;

FIG. 5 is a top plan view of the square-shaped suction cup according to the present application;

FIG. 6 is a bottom plan view of the square-shaped suction cup according to the present application;

FIG. 7 is a top front perspective view of the square-shaped suction cup according to the present application; and,

FIG. 8 is a top front perspective view of the square-shaped suction cup in using state according to the present application.
